UNITED STATES PATENT OFFICE.

ELBERT BROWN, OF TULARE, CALIFORNIA.

WHEEL-RIM.

1,238,879.

Specification of Letters Patent.

Patented Sept. 4, 1917.

Application filed March 6, 1917. Serial No. 152,818.

To all whom it may concern:

Be it known that I, ELBERT BROWN, a citizen of the United States, residing at Tulare, in the county of Tulare and State 5 of California, have invented certain new and useful Improvements in Wheel-Rims, of which the following is a specification, reference being had to the accompanying drawings.

- 10 This invention relates to certain improvements in wheel rims and has relation more particularly to a device of this general character of a demountable type designed for use in connection with inflatable tires; and 15 it is an object of the invention to provide a novel and improved device of this general character divided circumferentially into two sections together with means whereby said sections may be readily and conveniently 20 locked in assembled relation or can be easily separated when the requirements of practice necessitates.

The invention consists in the details of construction and in the combination and arrangement of the several parts of my improved rim whereby certain important advantages are attained and the device is rendered simpler, less expensive and otherwise more convenient and advantageous for use, 30 all as will be hereinafter more fully set forth.

The novel features of the invention will hereinafter be definitely claimed.

In order that my invention may be the 35 better understood, I will now proceed to describe the same with reference to the accompanying drawings, wherein—

Figure 1 is a transverse sectional view of a rim constructed in accordance with an embodiment of my invention;

Fig. 2 is fragmentary view of the under surface of my improved rim showing the retaining or locking means in inoperative relation; and

Fig. 3 is a view similar to Fig. 2 but showing the fastening means in locked relation.

As herein embodied, my improved rim is divided circumferentially into two sections 1 and 2 with one of the sections of a width 50 materially in excess of the width of the second section, and the adjacent margins of said sections 1 and 2 are reduced to afford the tongues or extensions 3 which overlap when the sections are in assembled relation 55 and which results in the opposed faces of the sections being substantially flush.

At predetermined intervals the sections of the rim are provided with locking means. As herein embodied, only one of said locking means is disclosed although in practice it is 60 to be understood that said locking means are preferably four in number and equidistantly spaced. As herein disclosed, a flat arm 4 is pivotally engaged, as at 5, with the under surface of the wider section 1 adjacent its reduced portion and said arm 4 is of such a length as to overlie the under surface of the coacting section 2.

A longitudinal margin of the arm 4 adjacent the outer end of said arm is provided 70 with an open slot 6 extending substantially transversely of the rim and adapted to receive the shank 7 of a headed stud 8 carried by the second or narrow section 2 and extending beyond the under or inner face 75 thereof.

The opposite longitudinal marginal portion of the arm 4 at a point substantially in alignment with the slot 6 is provided with the recess or notch 9 adapted to receive the 80 free end portion of the dog 10 pivotally engaged, as at 11, with the under surface of the section 2 adjacent the outer margin of said section and at a point intermediate the outer margin of said section 2 and the stud 85 8. When the dog 10 is seated within the recess 9 as indicated in Fig. 3, it will be perceived that the arm 4 is securely held in locked engagement with the stud 8. In order that the dog 10 may be readily forced 90 out of engagement with the arm 4 it is to be noted that the recess 9 and the outer end of the dog 10 are arcuate in form and disposed on a curvature concentric to the pivot of the dog 10.

In practice it is only necessary in order to remove a tire from the rim that the dog 10 of each of the fastening means be disengaged from the arm 4 whereupon the sections 1 and 2 may be readily separated after 100 the arm 4 has been freed from the stud 8. This requires a minimum of labor and time and dispenses with the use of tools other than a hammer or other implement capable of giving a striking blow. It will also be 105 self-evident that a tire may be applied to the rim with equal facility and convenience.

From the foregoing description, it is thought to be obvious that a rim constructed in accordance with my invention is of an extremely simple and comparatively inexpensive nature and is particularly well adapted

for use by reason of the convenience and facility with which it may be assembled, and it will also be obvious that my invention is susceptible of some change and modification 5 without material departure from the principles and spirit thereof and for this reason I do not wish to be understood as limiting myself to the precise arrangement and formation of the several parts herein shown in carrying out my invention in practice, except as hereinafter claimed.

I claim:

A tire rim divided circumferentially into two sections, the adjacent margins of the 15 sections being in overlying relation, one of said sections being of a width less than the second section, and coacting fastening means carried by said sections, said fastening means including an arm pivotally engaged

with one of the sections adjacent the inner 20 margin thereof, a stud carried by the second section in transverse alinement with the pivot of the arm, said arm being provided with a transversely directed open slot to receive said stud, and a dog pivoted to the 25 second section and adapted to engage the arm for holding said arm in engagement with the stud, a margin of the arm adjacent the closed end of the slot being recessed to receive the free end portion of the dog when 30 the arm is operatively engaged with the stud.

In testimony whereof I hereunto affix my signature in the presence of two witnesses.

ELBERT BROWN.

Witnesses:

MARY A. BROWN,
MABEL C. POTTER.
